UNITED STATES PATENT OFFICE.

JOHANN SANDNER, OF DÜSSELDORF, GERMANY, ASSIGNOR TO ANTON RICHARD, OF DÜSSELDORF, GERMANY.

ROLLING-MILL.

SPECIFICATION forming part of Letters Patent No. 767,314, dated August 9, 1904.

Application filed October 14, 1902. Serial No. 127,219. (No model.)

To all whom it may concern:

Be it known that I, JOHANN SANDNER, a citizen of Germany, residing at Düsseldorf, Germany, have invented certain new and useful 5 Improvements in Rolling-Mills, of which the following is a specification.

This invention relates to an improved mill for rolling iron and steel blocks into bars or tubes of superior density.

10 In the accompanying drawings, Figure 1 is a horizontal section through the operative part of a rolling-mill embodying my invention; and Fig. 2, an end view, partly in section, of the same.

15 The letters *a* and *b* represent two parallel shafts, which are driven in suitable manner. Upon shaft *a* are mounted a series of gear-wheels *c*, that alternate with idlers *c'* of less diameter. Upon the shaft *b* are mounted a 20 similar set of gear-wheels *c*² and intermediate smaller idlers *c'*². The relative arrangement is such that the gear-wheels *c* of shaft *a* are placed opposite the idlers *c'*² of shaft *b*, while the idlers *c'* are placed opposite the gear-wheels 25 *c*². The teeth of the gear-wheels *c* *c'* project outwardly and are arranged centrally upon the periphery of the wheels, so as to be flanked by two smooth or cylindrical rims, as shown.

Intermediate the shafts *a* and *b* are arranged 30 a series of parallel rolling-rings *r' r*², of which alternate rings *r' r*³, &c., are driven by the gear-wheels *c*² of shaft *b* and impinge against the idlers *c'* of shaft *a*, while the intermediate rings *r*² *r*⁴, &c., are driven by the gear-wheels 35 *c* of shaft *a* and impinge against the idlers *c'* of shaft *b*. The rings *r' r*², &c., are each provided with countersunk peripheral teeth *z*, flanked by smooth or cylindrical rims *o*. In this way the rings will be intergeared with 40 the driving-wheels *c* *c'* in such a manner that the pressure is taken off their teeth and transmitted to their rims.

In order to center the rolling-rings *r' r*², &c., and prevent their vertical displacement 45 I provide a pair of guide-rollers *e e'*, Fig. 2, which are arranged above and below the rings,

respectively, and are adapted to contact with the same.

Owing to the different diameters of the driving-wheels and idlers upon the shafts *a* 50 and *b*, the alternating rings *r' r*³, &c., will approach the shaft *a* more closely than the intervening rings *r*² *r*⁴, &c. In like manner rings *r*² *r*⁴, &c., will approach the shaft *b* more closely than the intervening rings *r' r*³, &c. 55 Each of the rings *r' r*³, &c., is provided with a central opening, which is in this way partly overlapped by the opening of the adjoining ring to form a draw-hole, which is of approximately oval shape, as indicated in Fig. 2. 60

The diameters of the openings in the rolling-rings *r' r*³ gradually diminish from left to right, while the surface of such openings tapers in the same direction, so that a coniform draw-hole is obtained. At its circumference 65 each of the openings is provided with a thread or spiral corrugation *s*, which serves to feed the metal through the mill. The height of this corrugation gradually diminishes from the first toward the last ring, so that the 70 rings jointly form a passage having a gradually flattening or vanishing thread. The last two rings, *r*⁸ and *r*⁹, are preferably made with smooth cylindrical openings and constitute finishing-rollers. 75

As thus far described, the mill is adapted for rolling bars. If it is designed for rolling tubes, a mandrel *d* is centered between the shafts *a* and *b* by being secured to a suitable support *d'*. 80

The operation is as follows: The shafts *a* and *b* are rotated to turn the rings *r' r*³, &c., by means of the gear-wheels *c* *c'*, and the hot metal *A* is introduced into the ring *r'* having the draw-hole of greatest diameter. The 85 thread *s* will during the rolling operation form a corresponding groove or corrugation in the metal and will thus feed the same through the draw-hole. Owing to the gradual flattening of the thread, this corrugation will be obliterated before the finished product leaves 90 the mill.

What I claim as my invention, and desire to protect by Letters Patent, is—

1. In a rolling-mill, a series of pairs of parallel overlapping rings arranged to form a progressively-reduced opening, in combination with oppositely-placed driving-wheels engaging said rings, substantially as specified.
2. In a rolling-mill, a series of pairs of parallel overlapping toothed rings arranged to form a progressively-reduced opening, in combination with a pair of shafts, wheels on said shaft engaging alternate rings, and idlers between the wheels, substantially as specified.
3. In a rolling-mill, a series of pairs of overlapping rings having a gradually-flattening internal thread arranged to form a progress-

ively-reduced opening, combined with oppositely-placed driving-wheels engaging said rings, substantially as specified.

4. In a rolling-mill, a series of pairs of overlapping rings having a gradually-flattening internal thread arranged to form a progressively-reduced opening, combined with a mandrel within the rings, and oppositely-placed driving-wheels engaging the rings, substantially as specified.

Signed by me at Düsseldorf, Germany, this 1st day of October, 1902.

JOHANN SANDNER.
